UNITED STATES PATENT OFFICE.

OLIVER MORLAND, OF BIRMINGHAM, ENGLAND.

MULTIPLE CARBON-SHEET BINDER.

SPECIFICATION forming part of Letters Patent No. 683,782, dated October 1, 1901.

Application filed June 19, 1900. Serial No. 20,892. (No model.)

To all whom it may concern:

Be it known that I, OLIVER MORLAND, printer, a subject of the Queen of Great Britain, residing at 31 Carlyle road, Edgbaston, 5 Birmingham, in the county of Warwick, England, have invented a certain new and useful Multiple Carbon-Sheet Binder, of which the following is a specification.

This invention relates to a multiple carbon-10 sheet binder or carbon-sheets used in connection with type-writers for duplicating or copying original matter at the same time as it is written. Usually such carbons are loose sheets which in use are placed in layers be-15 tween paper to bear the written and copied matter.

This invention is a multiple carbon-sheet binder or carbon-sheets built up in the manner hereinafter described and illustrated, the 20 last-named by the annexed sheet of drawings.

Figure 1 of the said drawings is a front elevation, Fig. 2 a vertical section, and Fig. 3 a transverse section, of the said carbon folio, the sections Figs. 2 and 3 being respectively 25 upon the lines A and B, Fig. 1.

In the figures a multiple carbon-binder comprising four carbon-sheets *a*, *c*, *d*, and *e* is shown, the top edges of the said sheets being bound together at *f* by a protecting sheet or 30 backing *g* of paper or other suitable material (said backing extending the full area of the carbon-sheet *e* and being turned over at *g*² in the manner shown) connected to the said carbon-sheets by a line of stitching *g*³ or 35 other suitable and preferably flexible fastening device, connecting the whole of the carbons together, so as to leave the turned-over edge *g*⁴ free. A tab or flap *h* is also formed upon the edge *g*⁴.

40 It will be seen from the sections, Figs. 2 and 3, that by so binding together the edges of the carbon-sheets a groove or pocket, with the stitching-line at the bottom of each, is formed between each carbon-sheet, between 45 the backing *g* and the last carbon-sheet, and between the turned-over edge *g*⁴ and the first carbon-sheet, into which said grooves or pock-

ets the ends of the sheets of paper to bear the written and copied matter can be tucked or inserted to materially help to hold them in position within the carbon-binder and set them true to each other. It will also be seen from the drawings that the backing *g* extends the whole surface of the carbon-sheets, so as to protect them from damage, the edges of the 55 said backing being cut true to or to register with the edges of the carbon-sheets. The turning over of the backing *g* at *g*² in the manner shown gives one edge only to be introduced into the type-writer around the 60 platen and greatly facilitates the introduction of the papers into the machine.

A multiple carbon-binder so formed has many further advantages, some of which are that there are no loose carbon-sheets requiring arrangement in the building up of a duplicating carbon-binder, the life of the carbons are extended by the backing protecting their edges, and the papers bearing the written and copied matter can be placed into position, with the line of stitching as a guide or setting as a security of the written matter on each sheet being written true or in line.

The tab or flap *h* is for laying hold of to shake the sheets of paper out of the binder 75 and from between the carbons.

Having now described my invention, what I claim, and desire to secure by Letters Patent, is—

In combination, a plurality of carbon-sheets 80 having trued edges, a back therefor formed of flexible material and bent upon itself to form a flap extending over the trued edges of said carbon-sheets, and a row of stitching 85 extending entirely across the said flap and through the same, the back and the carbon-sheets for connecting the latter to the former.

In testimony whereof I have hereunto set my hand in presence of two subscribing witnesses.

OLIVER MORLAND.
